TILTABLE CHAIR

Orva N. Smith, Berne, Ind.

Application June 11, 1937, Serial No. 147,754

4 Claims. (Cl. 155—57)

This invention relates to upholstered furniture, and has particular reference to a chair such as is adjustably and tiltably mounted on appropriate supporting means so that the seat is susceptible 5 of being disposed at varied inclinations with respect to the floor or other supporting surface.

The purpose of the invention is to provide a tilttable, shiftable chair and coacting base means making it possible to adapt almost any style or 10 form of a chair for coordination with said base means and to practically transform the complete assembly into a seat whose inclination may be adjusted to suit the occupant and to thereby promote restful comfort.

15 I am sufficiently conversant with the furniture trade and the prior art which comprehends it to appreciate that chairs and equivalent pieces of furniture are equipped with tilttable backs, adjustable seats, and other comforts to accommodate 20 the occupant. My aim is, therefore, to utilize what may be called an ordinary or conventional chair, upholstered or plain, wherein the same can be bodily shifted and tilted to maintain the back rest and seat in the same angular relation 25 with respect to each other, but to vary their position in relation to the floor.

Other features and advantages will become more readily apparent from the following description and drawings.

30 In the drawings, wherein like numerals are employed to designate like parts throughout the views:

Figure 1 is what may be called a side elevational view of a conventional upholstered chair 35 showing the attached supporting base unit therefor constructed in accordance with my ideas.

Figure 2 is a sectional and elevational view of the frame work detailing the orderly selected and coordinated features found best to serve the 40 needed purposes.

Figure 3 is a view similar to Figure 2 with certain of the features omitted for clearness of illustration of the principle of operation.

Figure 4 is a bottom plan view showing the 45 adapter means on one of the side rails of the base frame, that is, the frame of the base of the chair.

Figure 5 is an enlarged detail vertical section on the line 5—5 of Figure 2; and

50 Figure 6 is an elevational view of one of the leg members of the two-part base unit or support.

Referring now to the drawings by distinguishing reference numerals, it will be observed that the chair, which is an upholstered conventional 55 type is denoted by the numeral 7. As brought

out for better illustrative purposes in Figure 2, the back rest is denoted by the numeral 8 and a seat or base frame is denoted by the numeral 9. The latter part is generally rectangular in form, and in accordance with the present conception, opposed parallel side rails 10 thereof are provided with adapter devices to coordinate with the duplicate members of the two-part leg-equipped base units or members 11.

The base members are duplicate in construction. That is to say, each member or unit 11 includes supporting feet 12 to rest on the floor, and further includes a central riser whose upper curved surface 13 is in effect a seating crown for the chair frame 9. Said part 13 is thus of convex 15 form and functions as a fulcrum for the relatively tilttable and shiftable or slidable bodily adjustable chair 7. In its preferred embodiment, the base member 11 is in the nature of a longitudinally bowed leg frame. The central portion of the 20 under side thereof is provided with a keeper notch 14 to accommodate a binding or retention bolt 15 carried by the chair frame.

The adapter means on the chair frame which is associated with the member 11 by way of said 25 bolt 15 is in two parts. Each part comprises a retaining cleat 16 and an intervening rest or adapter element 17. The cleat 16 is secured by screws or similar fastenings 18 to the adjacent side rail, said fastenings 18 also serving to hold 30 in place the adapter element 17. The latter part is in the form of a relatively short block or equivalent piece of wood, as seen in Figure 3. The top thereof is flush with the corresponding top portion of the surrounding frame 9. The lower 35 edge portion is formed with a central clearance notch 19 coacting with the underlying crown 13, and further formed with a pair of longitudinally spaced and properly curved seating surfaces 20. The curvature of these surfaces corresponds to 40 the curvature of the crown portion of the base unit 11. Thus, in effect, the unit 11 fits between the rails 10 and cleat 16, allowing rest 17 to come down on top of it to provide the desired adjustable shifting and fulcruming coaction between 45 the base unit and chair.

It will be noted that the bolt 15 goes through the rail 10 and the cleat 16 (see Figure 5) and also extends through the keeper notch 14. The ends or end walls of the notch 14 constitute 50 abutments to limit the longitudinal or horizontal shift of the chair in relation to the base members 11. Also, the bolt hole in the cleat 16 is slightly enlarged, as indicated at 21, to accommodate the nut and threaded end of the bolt, as indicated 55

at 22. The opposite headed end of the bolt, as shown at 23, is rockable in a countersunk recess in the rails 10. Under this arrangement, the bolt, when slightly tilted or canted, as shown in Figure 5, obtains a binding contact with the adjacent or top edge portion of the notch 14, thus locking the chair on the base in any position to which said chair has been adjusted or tilted, as the case may be.

10 It is thought that the description taken in connection with the drawings will enable a clear understanding of the invention to be had. Therefore, a more lengthy description is thought unnecessary.

15 While the preferred embodiment of the invention has been shown and described, it is to be understood that minor changes coming within the field of invention claimed may be resorted to if desired.

20 I claim:

1. In a structure of the class described, a chair including a seat and an associated back rest, said seat embodying a base frame and said frame including adjoined side and end rails, cleats fastened to corresponding inner surface portions of the side rails, and adapter blocks interposed between the cleats and side rails, the lower edge portion of each adapter block being longitudinally curved and the central portion of the curve 30 including an elongated clearance notch, and a pair of base units for supporting said frame, each unit being longitudinally bowed with its bowed portion disposed between the adjacent rail and cleat and arranged in matching contact with the curved lower edge portion of the adapter block, the lower edge portion of said base unit having a notch therein, and a bolt located in said notch and connected with the adjacent cleat and rail.

2. In a structure of the class described, a chair including a seat and an associated back rest, said seat embodying a base frame and said frame in turn including complementary adjoined side and end rails, duplicate cleats fastened to corresponding inner surface portions of the side rails in opposed relationship, and adapter blocks interposed between the cleats and side rails, the upper edges of the cleats being substantially flush with the corresponding edges of said side rails, the lower edge portion of each adapter block being longitudinally curved from end to end to provide a concave chair supporting surface, and a pair of base units for supporting and tilting said frame, said base units being located in the existing pockets between the cleats and side rails, the upper edge portion of said base unit being longitudinally bowed to provide a convex supporting and fulcrumming surface for the entire chair,

the curvature of said convexed surfaces corresponding to the curvature of the under sides of said adapter blocks for matching coaction, and a single bolt passing through each cleat and adjacent portion of the side rail to maintain the parts assembled, said base units being provided with longitudinally spaced stop shoulders with which said bolts coact.

3. In a structural assemblage of the class described, a base frame including a side rail, an adapter block fastened to the inner surface of said rail and having its upper edge flush with the corresponding edge of the rail, said adapter block being of a length considerably less than said rail, and the under side thereof being longitudinally curved to provide a concaved friction supporting and tilting surface, a cleat disposed in parallelism with the rail and block and secured to the rail and forming a pocket between itself and said rail, a longitudinally elongated supporting and tilting unit, said unit having its opposite ends formed into floor contacting feet and having its intermediate portion located in the pocket between the rail and cleat, that surface of the unit underlying said block being longitudinally curved to provide a convex supporting and friction fulcrumming surface, the convexed surface matching the concaved surface of said block, the intermediate portion of said unit having formed therein a notch forming a bolt accommodation base as well as longitudinally spaced stop shoulders, and a single bolt fastened transversely through the rail and cleat and extending through said notch and bridging said pocket in the manner and for the purposes described.

4. In a structure of the class described, a chair including a seat and an associated back rest, said seat embodying a base frame, and said frame including adjoined side and end rails, cleats secured to corresponding inner surface portions of said side rails, and adapter blocks interposed between the cleats and side rails, the lower edge portion of each adapter block being longitudinally curved to provide a supporting and frame shifting and adjusting surface, and a pair of duplicate base units for supporting said frame, each unit being longitudinally bowed with its bowed upper edge portion disposed between the adjacent rail and cleat and arranged in matching contact with the curved lower edge portion of the complementary adapter block, the lower edge portion of said base unit being provided with longitudinally spaced stop shoulders, and an assembling and check bolt passing through the cleat and companion rail and located for limited bodily adjustment between said stop shoulders.

O. N. SMITH.
